Paterson

(57) **CLAIM**

The ornamental design for an impact wrench as shown and described.

DESCRIPTION

1. Impact wrench

1.1 is a top perspective view of an impact wrench embodying our new design;

1.2 is a front elevation view thereof;

1.3 is a rear elevation view thereof;

1.4 is a left side elevation view thereof;

1.5 is a right side elevation view thereof;

1.6 is a top plan view thereof;

1.7 is a bottom plan view thereof; and

1.8 is a bottom perspective view thereof.

The broken lines in the drawings illustrate portions of the impact wrench that form no part of the claimed design.

1 Claim, 8 Drawing Sheets
